UNITED STATES PATENT OFFICE.

CARL G. ALDRICH, OF SOMERVILLE, MASSACHUSETTS.

EYEGLASS-HOLDER.

1,233,158.

Specification of Letters Patent. Patented July 10, 1917.

Application filed April 14, 1913, Serial No. 760,885. Renewed October 10, 1916. Serial No. 124,898.

To all whom it may concern:

Be it known that I, CARL G. ALDRICH, a citizen of the United States, residing at Somerville, in the county of Middlesex and State of Massachusetts, have invented certain new and useful Improvements in Eyeglass-Holders, of which the following is a specification.

My invention relates to eyeglass holders and particularly to that type of eyeglass holder which comprises a spring actuated reel and a cord or chain connected therewith to which the eyeglasses are fastened. My invention has for its object to provide an improved holder of the class indicated, and the invention resides in the novel features of construction and arrangement set forth in the following description and particularly pointed out and defined in the claims at the close thereof.

In the accompanying drawings:—

Figure 1 is a central cross sectional view of an eyeglass holder constructed in accordance with my invention.

Fig. 2 is a section on line 2—2 of Fig. 1.

Fig. 3 is a plan view partly broken away and in section.

Fig. 4 is a detail hereinafter described.

Figs. 5 and 6 are details of the reel hereinafter described.

Having reference to the drawings, A represents a base plate which forms the back of the reel inclosing casing and B a cover that is secured to base plate A by means of ears b, Fig. 3. From the outer side of the base plate A projects a post a to which is pivoted the butt end of a pin a' which at its opposite end co-operates with a hook a² projecting from the base plate A. This pin a' serves, as usual, to fasten the device to the clothing of the user. On its inner face the base plate A is made with a central stud a³ provided near its inner end with a reduced cylindrical portion a⁴ on which is rotatably mounted a reel C held in place against a shoulder a⁵ on stud a³ by means of a screw D mounted in the stud a³, said stud being interiorly threaded to receive the shank of the screw with the head d of said screw bearing against the inner end of the reduced portion a⁴ so as to leave the reel C free to turn thereon.

The reel C comprises two cup shaped members c' and c² fastened together by means of prongs or ears c³ provided on member c². These prongs c³ are passed

through registering holes provided in member c' and clenched to lock the two members together. Within the member c² is secured by means of ears or prongs c⁴ a disk or plate 60 c⁵ made with two diametrically opposite pockets or recesses c⁶ in each of which is arranged a ball c⁷. The pockets c⁶ are made sufficiently large to permit of radial movement of the ball c⁷ into and out of the 65 pockets or recesses d' provided upon the inner side of the flange d² projecting from the head d of screw D. Each pocket c⁶ is made with a cam side c⁸ the purpose of which will appear later. In order to hold 70 the ball c⁷ against falling out of the pockets c⁶ when said balls are out of engagement with the screw D I provide a ring c⁹ which is forced into place within the member c². This ring c⁹ is preferably made from celluloid or other suitable transparent material. To the reel C is fastened one end of a cord or chain c¹⁰ which extends from the reel out through an opening b² provided through the wall of cover B and at its outer end this 80 cord or chain carries a snap hook c¹¹ by means of which the cord or chain is coupled to the eyeglasses.

Within the member c' is arranged a coiled spring c¹² whose outer end is fastened at 85 c¹³ to the member c' and whose inner end is made with a hook engaging a slot a⁶ provided in the stud a³.

Holders of this class are usually attached to the coat, vest or waist of the user and 90 when the glasses are not in use the cord c¹⁰ is fully wound upon the reel C and the glasses hang suspended close to the holder. When it is desired to use the glasses the cord c¹⁰ is pulled outward and as the reel 95 carrying the plate c⁵ is rotated in the direction of the arrow, Fig. 2, the cam side c⁸ lifts the uppermost ball c⁷ out of the upper pocket d' and at the same time the spring c¹² is wound up. When the desired length 100 of cord c¹⁰ has been drawn off from the reel the operator permits the spring c¹² to rotate reel C in the opposite direction until one of the balls c⁷ reaches and drops into the topmost pocket d' whereupon the reel is locked 105 against further movement in that direction under the influence of spring c¹². When it is desired to re-wind the cord c¹⁰ upon the reel C the operator by giving said cord a quick jerk causes the uppermost cam c⁸ to 110 throw the uppermost ball c⁷ out of its pocket d' and before said ball can fall back into

said pocket the spring c^{12} rapidly rotates reel C in a direction to wind the cord c^{10} thereon and this winding movement of the reel continues until the snap hook c^{11} engages the casing cover B. During this winding movement of reel C the balls c^7 are held at the outer extremities of the recesses c^6 by centrifugal force.

From the above description it will be seen that the entire reel mechanism of my improved holder is mounted upon the base plate A so that said mechanism can be completely assembled and adjusted before the cover B is applied. Also the construction shown and described is simple and efficient and cannot be easily disarranged. Moreover, the construction shown and described is extremely simple and will stand comparatively hard usage, whereas the constructions heretofore proposed have been relatively complicated and required delicate parts easily affected by strain and wear. In my improved holder the mechanism is compactly arranged and strongly constructed with the minimum number of parts.

What I claim is:

1. In an eyeglass reel of the character described the combination of a reel made at one end with a recess; a plate secured within said recess made with a ball holding pocket having one side thereof formed as a ball lifting cam; a ball mounted within said pocket; a retainer secured within the recess of the reel for holding the ball within its pocket, and a post on which the reel is rotatably mounted, said post co-operating with the ball to lock the reel against rotation in one direction.

2. An eyeglass holder comprising a casing; means upon the outside of the casing for attaching the holder to its support; a reel rotatably supported within the casing; a spring connected with the reel for rotating the latter in one direction; a cord or the like connected with the reel; a locking member mounted on said reel with provision for limited radial and angular movement relatively thereto; means connected with the casing and normally engaging said locking member to hold it against rotating with the reel in either direction, and a cam on the reel for lifting the locking member radially to free it from said holding means when the reel is rotated by the cord.

3. An eyeglass holder of the class described comprising a casing; means upon the exterior of the casing for attaching it to its support; a stud upon the interior of said casing provided with a ball receiving recess; a reel rotatably mounted on said stud made with a ball holding pocket; a cord or the like connected with said reel; a spring for actuating the reel in one direction; a

ball clutch member loosely confined in the pocket of the reel so as to have limited radial and angular movement independently of the reel, said ball normally occupying the recess of the stud to hold said reel against being rotated by the spring, and a tangentially disposed cam surface on the reel for positively lifting the ball out of the recess of the stud when the reel is rotated by the cord and while the recess holds the ball against angular movement.

4. An eyeglass holder comprising a casing made up of a base plate and a cover secured together; means upon the outer face of the base plate for attaching the holder to its support; an interiorly threaded stud upon the inner face of said base plate; a reel rotatably mounted on said stud; a screw mounted in said stud for holding the reel on the latter; a locking member mounted on said reel with provision for limited radial movement; a flange projecting from the head of said screw and formed with a radial pocket co-operating with said locking member to hold the reel against rotation in one direction; a cam on the reel for shifting the locking member radially upward when the reel is moved in the opposite direction; an actuating spring connected at one end with the reel and at its opposite end with said stud, and a cord or the like connected with the reel.

5. An eyeglass holder comprising a casing made up of a base plate and a cover secured together; means upon the outer face of the base plate for attaching the holder to its support; an interiorly threaded stud upon the inner face of said base plate; a reel rotatably mounted on said stud; a plate secured to one face of said reel made with a ball holding recess, one side of which is shaped to serve as a cam; a ball mounted in said recess and movable radially therein to a limited extent, said ball being adapted to be shifted radially outward by the cam side of said recess when the reel is moved in one direction; a screw mounted in said stud, the head of said screw being made with a pocket co-operating with said ball to hold the reel against rotation in the opposite direction; a ring surrounding the head of the screw and secured to the reel for holding said ball in its recess; an actuating spring connected at one end with the reel and at its opposite end with said stud, and a cord or the like connected with the reel.

In testimony whereof I have affixed my signature, in presence of two witnesses.

CARL G. ALDRICH.
